UNITED STATES PATENT OFFICE.

JOHN H. B. REA, OF LA FAYETTE, GEORGIA.

MUFFLER FOR GAS ENGINES.

Application filed June 23, 1921. Serial No. 479,816.

To all whom it may concern:

Be it known that I, JOHN H. B. REA, a citizen of the United States, residing at La Fayette, in the county of Walker and State 5 of Georgia, have invented certain new and useful Improvements in Mufflers for Gas Engines; and I do declare the following to be a full, clear, and exact description of the invention, such as will enable others 10 skilled in the art to which it appertains to make and use the same.

This invention relates to an improved muffler for explosive engines, and it is the principal object of the invention to so 15 construct the same that it will practically eliminate all undesirable noises caused from the explosions occurring in the engine cylinders due to the peculiar construction which causes the escaping gases to take an extremely free but tortuous passage through 20 this muffler.

Another object of the invention is to generally improve upon devices of this class by the provision of one of extreme simplicity and durability which is composed of 25 ready marked parts, including ordinary pipes, fittings and couplings, all of the parts being connected together in such a way that they can be easily and readily separated for 30 making repairs and cleaning.

Other objects and advantages of the invention will be apparent during the course of the following description.

In the accompanying drawings forming 35 a part of this specification and in which like numerals are employed to designate like parts throughout the same:

Figure 1 is a side elevational view of a muffler constructed in accordance with this 40 invention.

Figure 2 is a central longitudinal sectional view through the same.

In carrying out the invention, I make use of a relatively large pipe section 1 which 45 is externally screw-threaded at opposite ends to permit reducer couplings 2 to be attached thereto. Screwed into these couplings are nipples 3 and screwed into these nipples are pipes 4 and 5 which are considerably 50 smaller in diameter than the first named pipe 1. Pipe 4 as will be seen leads from the exhaust manifold on the engine while pipe 5 extends into the large pipe 1 and has its inner open end closed by an ordinary screw-cap 6. It may be pointed out

that this pipe 5 is provided with a plurality of openings 7 to permit the gases to enter the same as will be seen later. Also threaded onto the screw-threaded inner end of this pipe 5 is a substantially conical coupling 8 which together with the cap 6 provides a way of deflecting the entering gases and causing them to be evenly distributed throughout the entire area of the muffler. This last named coupling 8 carries a short 60 length of pipe 9 which terminates adjacent one end of the pipe 1 and is sufficiently large to surround the pipe 5 and provide a space between these pipes to permit the gases to take the course of the arrows, that is, to 65 permit the gases to pass through the pipe 1 and between the pipes 5 and 9 and into the former through the aforesaid openings 7. The pipe 5 if desired may be extended beyond the nipples 3 to permit a coupling 10 70 to be connected thereto, this coupling being in turn connected with a pipe 11 which leads to the rear end of the machine, in the usual 75 way.

In operation, the gases from the exhaust 80 manifold pass through the pipe 4 into the adjacent end of the muffler. Upon entering the latter, they strike the cap 6 and deflector coupling 8 and are caused to be evenly distributed throughout the entire area of the 85 muffler. The pressure of the incoming gases causes the gases then in the muffler to pass between the pipes 9 and 5 and finally into the latter through the openings 7. It is then obvious that they pass from this pipe 5 90 into the pipe 11 where they are permitted to escape into the atmosphere in the usual 95 way.

By carefully considering the description 100 in connection with the drawing, persons familiar with devices of this class will doubtless be able to obtain a clear understanding of this invention. It is therefore thought unnecessary to describe the same in more detail or enter a more lengthy description.

The form of the invention herein shown and described is preferred, yet, it is to be understood that within the scope of the subjoined claim, slight changes may be resorted to if desired.

I claim:

A muffler for explosive engines comprising a comparatively large pipe externally screw-threaded at its opposite ends, reducer-couplings threaded on said ends, nipples

110

threaded into said couplings, a comparatively small pipe extending through one of the nipples and into said large pipe, being open at its ends and provided with a plurality of holes, a cap closing the inner end of the said small pipe, another coupling carried by the latter, and another pipe de-

tachably connected with said other coupling, surrounding and spaced from said small pipe and extending into close proximity to one of the aforesaid reducer couplings.

In testimony whereof I have hereunto set my hand.

JOHN H. B. REA.
